UNITED STATES PATENT OFFICE

EINAR T. ZACHRISON, OF CHICAGO, ILLINOIS

MECHANISM FOR PLAYING STRINGED INSTRUMENTS

Application filed April 18, 1929. Serial No. 356,224.

The present invention relates to self-playing stringed instruments, and more in particular to a novel construction of the means and method of automatically playing a stringed instrument.

Among the objects of my invention are to provide a novel construction of automatic device adapted to play stringed instruments; further to provide a novel system of pneumatic means for fingering and picking the strings of an instrument; further to provide a novel means and method of picking the strings; further to provide a construction adapted to pick the strings on the upstroke and to prevent the engagement of the picking device with the strings when said device is returned to its normal inoperative position; further to provide a novel mechanism adapted to control the modulation of the tones; further to provide a novel construction of maximum simplicity, efficiency, economy and ease of operation; and such further objects, advantages and capabilities as will later more fully appear.

My invention further resides in the combination, construction and arrangements of parts illustrated in the accompanying drawings, and while I have shown therein a preferred embodiment, I desire it to be understood that the same is susceptible of modification and change, without departing from the spirit of my invention.

In the drawings:

Fig. 1 is a top plan view of my construction, with portions of the fingering devices broken away to more clearly disclose the arrangement thereof.

Fig. 2 is a view in side elevation with portions thereof broken away, of the construction disclosed in Fig. 1.

Fig. 3 is a view in rear elevation, with a portion of one of the valve members in section.

Fig. 4 is a fragmentary view, part in side elevation and part in cross section, of the means and method of picking the strings.

Fig. 5 is a view similar to Fig. 4, but showing the position of the arm members after the string has been picked.

Fig. 6 is a view in vertical cross section taken on the line 6—6 of Fig. 1.

Fig. 7 is a view in vertical cross section taken through one of the double or dual pneumatics.

Referring more particularly to the drawings, the numeral 1 refers to a stringed musical instrument such as a banjo, mandolin, or the like, provided with a plurality of strings 2. The instrument shown is provided with four strings, although an instrument with any desired number of strings, may be played. In order to properly position the instrument and provide a base for its support, I provide a frame 3 having a series of vertical and horizontal supporting members, and a stand or supporting member 4, which is made adjustable by means of a set screw 5.

As shown in Figs. 1 and 2, I provide a series or plurality of fingering levers 6, which are connected to arms or plunger wires 7 and 7^a, and which are adapted to press against a string at any desired location. The other end of these arms or plunger wires are connected to the lower portion or base of a plurality of pneumatics 8. The plunger wires 7 and 7^a are threaded at their lower end and are provided with nuts 7^b allowing for adjustment of the length of the wires, which in turn allows for an adjustment of the pressure applied to the strings by the fingering levers 6.

In order to operate the fingering pieces, it is necessary to cause the respective pneumatic connected to that particular fingering device to operate. This is done by causing the pneumatic to collapse by means of suction provided in a tubing or hose 9 attached to the rear of a pneumatic action 10. This pneumatic action comprises three rows of spaced openings or inlets 11 positioned in the front or forward portion of spaced longitudinal compartments 12. Each of the compartments 12 is provided with an air inlet 13 having a small vent 13^a, the inlet leading to a circular opening 14 which is adapted to be closed by means of a valve 15. This valve comprises a diaphragm or seat 16 of leather or the like, stem 17, and an upper seat 18, adapted to close an opening 19 in a top plate 20. When air is caused to flow through the

opening 11, and into the cylindrical opening 14, the valve is raised and then seated against the plate 20, causing the upper seat 18 to close the opening 19. Channels 21 are connected to a pipe 22, connected to a source of suction, such as a suction pump or the like (not shown). The source of suction draws the air through outlets 23 and tubes connected thereto and around the valve stem. It is to be understood that each of the compartments and valves are similar in construction.

In regard to the timing of the fingering levers in conjunction with the picking devices in order to insure a pure undistorted tone, it is necessary that there be a proper sequence to the functioning of the fingering levers and picking devices. For example: suppose it is desired to play the note G on the tenth fret on the first or A string. The corresponding fingering lever for said G note is raised and impinged against the string just below the fret, just an instant before the corresponding picking device is set in motion. This is essential to insuring a pure, undistorted tone. Next, suppose the note C on the third fret on the same A string is to be played, the pneumatic operating fingering lever for the note G remains collapsed until the pneumatic which controls the fingering lever for the note C is operated. This will prevent any unnecessary vibrations of the said string and will therefore result in only a true note. This will also apply if the above notes were reversed in their order, it being understood that the other strings will operate on the same principle, and in a like manner. However, this principle need not necessarily be applied if, for example, the note C on the third fret of the first or A string is to be played, and the note G on the fifth fret of the second or D string is also to be played.

As there are no fingering devices for the open string notes; i. e. A for the first string, D for the second string, G for the third string, and C for the fourth string, it is essential for any fingering lever which is being operated to remain impinged against its particular string until said open note on that particular string is to be played. The length and timing of the perforations on the music roll will govern the same.

In order that the strings may retain their tune for a reasonable length of time, it is preferable that the same be made of steel. The tuning pins and pin block should be somewhat similar in construction to those of a piano.

Located below the musical instrument and in the frame of the base or housing I have provided four dual or double pneumatics, numbered 24, 24^a, 25 and 25^a. These dual or double pneumatics are each provided with an upper inlet 26 and lower inlet 27. The top of each pneumatic is provided with a prolonging arm or projection 28, while the

bottom is provided with a prolonging arm or projection 29, the upper arms or projections operating through the medium of rods or plunger wires 30 and 31, which are in turn connected through pivotal lever arms 32, to each of which is connected a pick 33. As clearly disclosed, each of the rods or plunger wires 30 and 31, and the lever arms 32 and picks 33 connected thereto, are similar in construction, while each of the rods or plunger wires 30^a and 31^a connected to the lower half of the double pneumatics, and the lever arms 32^a are also similarly constructed. The lever arms 32, to which are attached the picks 33, are connected to the upper half of the double or dual pneumatic, and perform the picking operation. The rods or plunger wires 30, 31, 30^a and 31^a are threaded and made adjustable by means of nuts 34. The upper lever arms 32, as more clearly disclosed in Figs. 4 and 5, are pivoted at 35 upon a projection 36, connected to a second lever arm 37 pivoted at 38 upon a flange or standard 39, connected to a horizontally extending supporting brace 40 of the frame. The lower lever arms 32^a are pivoted at 41 to a flange or projection 42, suitably attached to the brace arm 40 of the frame. At the outer end of each of the lower lever arms 32^a, is provided a projecting pin or plunger 43, the upper ends thereof passing through openings 44 in a plate 45. The upper end of the plunger or pin 43 impinges against the lower surface of the lever arm 37 of the upper or picking mechanism, and is adapted to raise the same.

In the picking operation, the plunger wires or rods 30, connected to the upper half of the dual or double pneumatic, are adapted to be lowered upon the collapse of such upper pneumatics, the lowering of these plunger wires or rods raising the picks 33 in the position shown in dotted outline in Fig. 4. This is the first half of the picking stroke. The rods or arms 31^a connected to the lower half of the double or dual pneumatics, when collapsed, pushes up the plunger and the lever arms 37 and 32, and strikes or picks the string, as shown in Fig. 5.

In the operation of the mechanism, I provide a perforated roll 46, which is adapted to pass over a tracker board 47, provided with ducts, to which are connected a plurality of tubes. Tubes 48, equal in number to the number of notes of the stringed instrument, are connected to the openings 11 in the base of the pneumatic action 10. Other tubes 49 are connected to the tracker board, and lead to the openings 11 in the pneumatic action for operating the picking mechanism, while still other tubes 50 lead from the tracker board to openings 11 in the pneumatic action for operating pneumatics 51 and 52 of an expression device.

From the rear of the pneumatic action,

tubes 9 lead to the pneumatics of the fingering mechanism. Tubes 53, connected to the middle row of the pneumatic action, pass to the upper half of the double pneumatics 24 and 24a, while tubes 54 from this middle row pass to the upper half of the double pneumatics 25 and 25a. These tubes 53 and 54 connect with the inlets 26 of the upper half of the dual pneumatics. Connected to the inlet 27 of the lower half of the upper double pneumatics, I provide tubes 55, while to the inlet 27 of the lower half of the lower double pneumatics, I provide tubes 56. Connected to the upper row of the pneumatic action, I provide tubes 57 and 58, connected to the pneumatics 51 and 52 respectively of the expression device.

In the operation of the double pneumatics for picking the strings, the air passes through an uncovered perforation in the roll, and then through the tubes to the pneumatic action. When the valve 15 is unseated, suction passes through the tubes 53 and the top half of the double pneumatic 24, collapsing the same against the action of the spring 59. The plate or prolonger arm 28 of this upper pneumatic pulls down on the rod or plunger wire 30, of whichever string is to be played, and through the medium of the lever arm 32 places the pick 33 in position for picking operation. The rear end 60 of the prolonger arm 28, being raised when the upper pneumatic collapses, opens the valve 61 by means of a regulating button 62, and allows air to pass downwardly through a tube or hose 63 to the inlet 11 on the bottom row of the pneumatic action. The air passing through the tube or hose 63 causes the valve 15 to unseat, and allows suction through the tube or hose 55 into the inlet of the lower half of the pneumatic, thus causing the same to collapse. The collapsing of the lower pneumatic lowers the arm 30a of the string to be picked, and through the medium of the lever arms 32a and plunger 43, raises the lever arms 37 and 32 which push the pick upwardly, thus causing the same to pick the string. It is to be understood that the same operation exists with reference to each of the four double pneumatics for picking the four strings.

When the perforations in the roll for picking the strings are closed, and it is desired that the pick be placed in its normal inoperative position, prior to the picking engagement, the upper pneumatic expands and raises the rod or plunger wire 30, which raises the outer end of the lever arm 32 and brings the pick into the position shown in the dotted outline in Fig. 5. As soon as this pick is in this dotted line position, the bottom pneumatic of the dual or double pneumatic is opened or expanded, thus raising the rod or arm 30a and bringing the pick into its normal position and ready to again pick a string.

The expanding of the pneumatics is taken

care of by reason of the springs 59, and the air passing through the openings 19 of the plate 20 whenever the diaphragm 16 is seated over the opening 14.

When it is desired to soften or produce a pianissimo tone, the same is taken care of by means of an expression device. In order to operate the same, I provide the pneumatics 51 and 52, to which are connected the tubes or hose 57 and 58, respectively, which as shown are connected to the outlets of the first and second compartments of the upper row in the pneumatic action. In this operation, the air passes through the perforation in the tracker board, through a hose or pipe 50 into the pneumatic action. This unseats the valve 15 and allows suction to pass from the pipe 22 into the pipe 57 which collapses the pneumatic 51. The construction for operating the pneumatic 52 is similar to that operating the pneumatic 51. When the pneumatic 51 and 52 are collapsed, a prolonger arm 64, attached to the lower end thereof, is pulled downwardly. Each arm in turn draws its adjustable rod or plunger wire 65 and 65a downwardly, each of these arms or wires being attached to a pair of valve mechanisms 66 through the medium of a connecting rod 67. These valve mechanisms are pivoted to the frame at 68 and are adapted to be lowered whenever the pneumatic is collapsed. By lowering the valve construction, the valves 61 are drawn closer to the regulating button 62, thus overcoming a large percentage of the lost motion. The opening of the valve allows air to pass downwardly to the tubes or pipes 63 of the upper valve members, and 63a of the lower valve members. Springs 69 quickly return the pneumatics 51 and 52 to their extended or open position. The function of the valves in the expression devices is to collapse more quickly the lower half of the double pneumatics, which operate the picking mechanism. This raises the pick with greater rapidity and prevents the same from getting a firm grip upon the string, thus softening the tone emanating therefrom. The valves operated by the pneumatic 51 function for the treble strings, while the valves operated by the pneumatic 52 function for softening the tones of the bass strings.

From the above description and the disclosure in the drawings, it will be seen that I have provided a novel construction of means and mechanism for automatically and pneumatically playing a stringed instrument. Although I have shown only a few of the tubes leading to the pneumatics of the fingering mechanism, it is to be understood that these tubes are similar in construction, and perform a similar operation as those disclosed in the drawings. The fingering mechanism is adapted for playing any type of stringed instrument, while the picking mechanism is adapted for actuating the strings of any type

of stringed instrument, such as a banjo, mandolin, guitar, or the like, provided with any number of strings. The pneumatic action is provided with openings, to which are attached tubes or other mechanism for rewinds, replays, action cut-offs, etc. The speeding up of the roll may be controlled by suction or by motor drive, such as a friction belt or chain.

Having thus disclosed my invention,

10 I claim:

1. Mechanism for automatically playing a stringed instrument, comprising a series of levers for fingering the strings, means for picking said strings, and means associated with said picking means for modulating the tones emanating from said strings.

2. Mechanism for automatically playing a stringed instrument, comprising means for fingering the strings of said instrument, 20 means for actuating said strings, and means associated with said actuating means for modulating the tone emanating from said strings.

3. Mechanism for automatically playing a 25 stringed instrument, comprising means for fingering the strings of said instrument, means for actuating said strings, and valve mechanism associated with said actuating means for modulating the tones emanating from said strings.

4. Mechanism for automatically playing a stringed instrument, comprising means for fingering the strings of said instrument, means for actuating said strings, and pneumatically operated means for modulating the tones emanating from said strings.

5. In a mechanism for automatically playing a stringed instrument, picking means therefor comprising a system of automatically operated lever arms, a pick on one of said lever arms, and means for raising said pick to strike a string on the upstroke and for preventing impingement of said pick on said string during the downstroke.

40 6. In a mechanism for automatically playing a stringed instrument, an automatically operated lever arm therefor, a pick mounted on said lever, means for causing said pick to strike a string on the upstroke, and means for preventing the impact of said pick on said string during the downstroke.

7. In a mechanism for automatically playing a stringed instrument, a pivoted arm therefor, a pick mounted on said arm, means for causing said pick to strike a string on the upstroke of the arm, and pneumatically operated means for preventing impact of said pick on the downstroke.

60 8. In a mechanism for automatically playing a stringed instrument, a pivoted arm therefor, a pick mounted on said arm, pneumatically operated means for causing said pick to strike a string on the upstroke of the arm, and pneumatically operated means for

preventing impact of said pick on the downstroke.

9. Mechanism for automatically playing a stringed instrument, comprising means for fingering the strings of said instrument, means including lever arms for picking said strings, and means associated with said arms for modulating the tones produced by said strings.

10. Mechanism for automatically playing a stringed instrument, comprising means for fingering the strings of said instrument, means including lever arms for picking said strings, and pneumatically operated means associated with said arms for modulating the tones produced by said strings.

11. Mechanism for automatically playing a stringed instrument, comprising means for fingering the strings of said instrument, means for picking said strings, and means for varying the stroke of said picking means for giving expression to the tones produced.

12. Mechanism for automatically playing a stringed instrument, comprising means for fingering the strings of said instrument, means for picking said strings, and pneumatically operated means for varying the stroke of said picking means for giving expression to the tones produced.

13. Mechanism for playing a stringed instrument, comprising means for fingering the strings and means for picking said strings, said picking means including lever arms, one of which is provided with a pick, and a plunger adapted to raise said lever arm and pick for engaging a string.

14. Mechanism for playing a stringed instrument, comprising means for fingering the strings and means for picking said strings, said picking means including lever arms, one of which is provided with a pick, a plunger on the other of said arms adapted to raise said lever arm and pick for picking a string.

15. Mechanism for playing a stringed instrument, comprising means for fingering the strings and means for picking said strings, said picking means including pivoted arms, one of which is provided with a pick, and a member adapted to raise said arm and pick for impinging a string.

16. Mechanism for playing a stringed instrument, comprising means for fingering the strings and means for picking said strings, said picking means including a pair of arms fulcrumed intermediate the ends thereof, one of said arms being provided with a pick, and a member on the other of said arms adapted to raise said first mentioned arm and pick into picking engagement with a string.

17. Mechanism for automatically playing a stringed instrument, comprising means for fingering the strings of said instrument, means for picking said strings, said picking means including a pivoted arm provided with a pick, and a plunger adapted to raise said
